Passmore & Heckert.

Railroad Switch.

N° 64,138.

Patented Apr. 23, 1867.

United States Patent Office.

HENRY E. PASSMORE AND GEORGE A. HECKERT, OF YORK, PENNSYLVANIA.

Letters Patent No. 64,138, dated April 23, 1867.

IMPROVED RAILROAD SWITCH.

The Schedule referred to in these Letters Patent and making part of the same.

TO ALL WHOM IT MAY CONCERN:

Be it known that we, HENRY E. PASSMORE and GEORGE A. HECKERT, of the borough of York, in the county of York, and State of Pennsylvania, have invented a new and useful improvement in railroad switches, which we call an "Improved Railroad Switch;" and we do hereby declare that the following is a full, clear, and exact description of the construction and operation of the same, reference being had to the annexed drawings, making a part of this specification, in which—

Figure 1 is a plan of switch, part of main track, and siding.

Figure 2, section through line A B, cutting outer and guard-rails, and showing end of pointed spring-rail on slide-plate.

Figure 3, section through pointed spring-rail and lug slide-plate.

Figure 4, longitudinal section of single-lipped switch-rod.

C, pointed spring-rail; D, notched guard-rail; E, slide-plate under pointed spring-rail; F, lug slide-plate; G, single-lipped switch-rod.

The nature of our invention consists in providing two pointed spring-rails, made of steel or tempered iron, moving on slide-plates between the outer rails and guard-rails, adjusted by means of the single-lipped switch-rod in passing from main track on to siding, and self-adjusting by means of the pointed spring-rails in passing from siding on to main track.

The operation of this switch is as follows: The wheels of a car coming off of siding on to main track force the pointed spring-rails C C back against the notched guard D and outer rail, and when the wheels of the car clear, the pointed spring-rails C C fly back, and the line of the main track is unbroken.

Now what we claim as our invention, and desire to secure by Letters Patent, is—

1. The pointed spring-rails C C, moving on the slide-plates E E, and lug-plates F F, in combination with rails X X.

2. The "double-notched guard-rails" D D, in connection with the pointed spring-rails C C, to guard the wheels from striking the points of the said spring-rails.

3. The single-lipped switch-rod G, which allows the pointed spring-rails C C to move back, in combination with spring-rails, &c.

4. The combination of the pointed spring-rails C C, moving on the slide-plates E E, the lug-plates F F, and the single-lipped switch-rod G in connection with the guard-rails D D, in the manner and for the purpose herein substantially set forth.

HENRY E. PASSMORE,
GEO. A. HECKERT.
